ADJUSTABLE HANGER

James Speranza, Wilmerding, Pa.

Application October 16, 1939, Serial No. 299,752

2 Claims. (Cl. 156—23)

This invention relates to adjustable hangers for curtains, shades, draperies and the like for window and door openings, and its general object is to provide a hanger that is adjustable in an easy and expeditious manner to fit windows and door frames of various widths, and is held in fixed relation thereto, against casual displacement or removal, in that the hanger includes telescopically associated rod sections having toothed frame receiving brackets secured thereto, that not only set up a biting engagement with the side faces of the frame and are resiliently urged accordingly, but the brackets include lugs that are urged firmly against the front faces of the frame.

Another object is to provide an adjustable hanger that includes a pair of companion rods for receiving draperies, portières or the like, the rods being mounted for swinging movement for disposing the draperies away from the window, to facilitate the removal and replacement of curtains and shades, as well as providing ready access to the window for cleaning the same.

A further object is to provide a hanger that is not only adjustable to fit window and door frames of various widths, but includes adjustable shade brackets for receiving shades of various lengths.

Another object is to provide an adjustable hanger of the character set forth, that can be readily applied and removed with respect to a frame, is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view of one form of my hanger for curtains, draperies and the like, and is illustrated applied to a frame.

Figure 2 is a top plan view of the form shown in Figure 1, with the curtain rod in section.

Figure 3 is a perspective view of a slightly modified form of bracket for the form of Figures 1 and 2.

Figure 4 is a perspective view of a modified form for use with curtains, draperies and shades, and is illustrated applied to a frame.

Referring to the drawing in detail, the letter A indicates a window or door frame, as the forms

shown in Figures 1 to 3 are designed for supporting curtains, draperies, portières or the like with respect to either a door or window frame, while the form of Figure 4 is designed for use with a window frame only, indicated by the letter B, as the latter form includes window shade brackets.

Again, referring to the form of Figures 1 and 2, the reference numeral 1 indicates the rod brackets of that form, there being a pair of identical companion brackets and each bracket is stamped or otherwise made from plate material to provide a flat substantially rectangular vertically disposed body including a reduced rearwardly directed extension having teeth 2 formed on its rear end and bent at right angles thereto, while formed on the upper and lower edges of the body at the opposite or front end thereof is a pair of inwardly directed superimposed ears 3 arranged at right angles to the body and having registering openings therein for a purpose which will be later described. Struck from the lower corner of the body of each bracket, and bent at right angles thereto for disposal inwardly therefrom is a lug 4 to bear against the front face of the frame.

One of the brackets has secured to the body thereof one end of a relatively long tubular rod section 5, while secured to the body of the other bracket is one end of a relatively short tubular rod section 6. The sections extend inwardly from the brackets and the manner of securing the same thereto is of extreme importance. It is accomplished by inserting the sections within openings in the brackets and thence forcing the metal against the opposite faces of the brackets to provide annular channel grooves 7 receiving the edges of the openings therein, as clearly shown in Figure 2. By that construction, it will be obvious that separation of the rod sections with respect to the brackets is practically impossible, and the use of threaded or other fastening means for securing the brackets and sections together has been eliminated.

Telescopically mounted on the rod sections 5 and 6, is an intermediate rod section 8, and one end of the section 8 is provided with an annular recess having mounted therein a reinforcing collar 9 provided with a threaded opening registering with an opening in the section 8 for receiving a set screw 10 to secure the section 8 in adjusted positions with respect to the section 5.

The inner end of the section 6 is reduced and provided with a cross member 11 for receiving the hooked end 12 of a coiled tension spring 13 while the opposite hooked end 14 is mounted on a pin 15 transversing the section 8 a considerable

distance inwardly of the free end thereof, as best shown in Figure 2. By that construction, it will be obvious that the section 8 is freely movable on the section 6 at all times, but is fixed with respect to the section 5 by the set screw 10.

When it is desired to apply the hanger to the frame A, the section 8 is adjusted on the section 5 for the disposal of the teeth in biting engagement with the outer side faces of the frame, and the spring will retain the teeth accordingly, yet will allow removal of the hanger from the frame without changing the adjustment of the section 8. The brackets are associated with the frame in a manner whereby the lugs 4 are engageable with the front faces thereof, so as to cooperate with the teeth and the spring for holding the hanger fixed to the frame against casual removal or displacement.

20 The rod brackets of the form of Figure 3 are similar in many respects to those of the form of Figures 1 and 2, but the brackets of the latter form are designed for the teeth thereof to engage the outer side faces of the frame, while the brackets of the form of Figure 3 are designed
25 for the teeth to engage the inner side faces of the frame, with the result the only difference in the bracket structure is that the teeth 16 of the bracket 17 extend outwardly therefrom and the same is true with respect to the lug 18, or in
30 other words, the teeth 16 and lug 18 are disposed in a direction opposite from that of the teeth 2 and lugs 4. While only one of the brackets 17 is shown, it will be obvious that two brackets are
35 necessary and the bracket shown has a short rod section 19 secured thereto in the same manner in which the rod section 6 is secured to its bracket. However, the rod section 19 preferably has a closed free end for receiving one end of a compression coil spring not shown, while the opposite end of the compression coil spring is engaged with the pin 15 of an intermediate rod
40 section 8. The compression spring is necessary for use with the brackets of the form of Figure 3, for forcing the teeth thereof against the inner
45 side faces of the frame, as will be apparent. The brackets 17 are likewise provided with superimposed ears 20 having registering openings therein.

Regardless of whether the brackets 1 or 17
50 are used, a pair of drapery or portière rods 21 are
mounted thereon, there being a rod 21 for each
bracket of a pair, and it will be noted as best
shown in Figure 1 that the rods 21 are identical
55 and each includes a square cornered portion for
receiving a drapery or portière thereon. The rods
are bent at right angles adjacent one of their
ends, and their bent portions are reduced to pro-
vide shoulders and trunnions 22, the shoulders
bearing against the upper ears and the trunnions
60 being mounted in the openings of the ears, for
swinging movement of the rods 21 toward and
away from each other, to be disposed parallel
with the frame or at forward angles thereto, as
will be obvious upon inspection of Figure 1. By
65 that construction, it will be seen that the rods
21 are readily detachable from the brackets and
that the swinging movement thereof facilitates
the application and removal of curtains with
respect to the sectional curtain rod, as well as
70 cleaning of a window in the event the hanger is
applied to a window frame.

The form of Figure 4 is primarily designed for use with the window frame, as previously set forth, and likewise includes a pair of brackets 75 23 each being provided with a rectangular body

having teeth 24 formed on the rear ends thereof and bent at right angles thereto for biting engagement with the frame B, and formed on the body intermediate its ends are apertured ears 25 outwardly directed therefrom and disposed in superimposed relation with respect to each other, as shown. The ears of the brackets 23 are adapted to receive the trunnions 26 formed on the right angle bent ends 27 of a pair of drapery or portière rods 28 for swinging movement thereof toward and away from each other for the same purpose as the rods 21. 5 10

The form of Figure 4 likewise includes a sectional rod which is identical to that of the form of Figures 1 and 2, that is the sections are telescopically mounted and the intermediate section 29 is connected to one end section 30 by a tension spring for drawing the teeth 24 in biting engagement with the frame B, and the intermediate section is adjustably associated with the other end section 31, as well as fixed in adjusted position thereon by a set screw. 11

Flat arms 32 arranged in pairs extend inwardly from the brackets 23 for receiving the usual flat telescopically mounted curtain rods, as will be apparent.

Formed on the bodies of the brackets 23 and depending therefrom preferably midway their ends are the vertical portions 33 of sectional shade bracket members that include horizontal portions 34 directed toward each other and terminating at their inner ends in upwardly directed guide tongues 35. Slidably mounted on the horizontal portions 34 are trunnion receiving portions 36 and 37, having slots 38 extending longitudinally thereof for receiving the guide tongues 35 and set screws 39 for securing the trunnion receiving portions in adjusted positions with respect to the horizontal positions. The upturned end 40 of the portion 36 is provided with a slot 41 for receiving the flat trunnion of a shade roller, while the upturned end 42 of the portion 37 has an opening 43 therein for receiving the other trunnion of the shade roller.

The vertical portions 33 have inwardly extending members 44 formed thereon and which have their inner ends bent at right angles upon themselves to provide lugs 45 engaged with the front faces of the frame B, for cooperation with the teeth 24 and the spring of the sectional rod for securing and supporting the hanger with respect to the frame, as clearly shown in Figure 4. 45

It is thought from the foregoing description that the advantages and novel features of the invention will be readily apparent. 55

It is to be understood that changes may be made in the construction and in the combination and arrangement of the several parts, provided that such changes fall within the scope of the appended claims. 60

What I claim is:

1. In a curtain and drapery hanger including a pair of brackets, spring urged adjustable means secured to and bridging the brackets for mounting the latter with respect to a window frame, each bracket comprising a flat vertically disposed body, frame receiving teeth formed on each body, a lug formed on each body for engagement with the frame to cooperate with the teeth and the spring urged means for securing the brackets to the frame, superimposed ears formed on the body of each bracket and right angularly directed therefrom, and a pair of companion rods having one of their end portions bent at right angles to the remaining portions thereof and reduced

to provide shoulders bearing against the upper ears and trunnions mounted in the ears for swinging movement of the rods toward and away from each other for disposal thereof parallel with the frame in end to end relation or at forward angles thereto.

5. 2. In a curtain, drapery and shade hanger including a pair of brackets, spring urged adjustable means secured to and bridging the brackets 10 for mounting the latter with respect to a window frame, each bracket comprising a flat vertically disposed body, frame receiving teeth formed on the body, a vertical portion for each bracket and depending from the body thereof, rearwardly 15 directed portions formed on the depending por-

tions, lugs formed on the rearwardly directed portions and engageable with the frame to cooperate with the teeth and the spring urged means for securing the brackets to the frame, horizontal portions formed on the vertical portions and inwardly directed therefrom, upwardly directed guide tongues formed on the inner ends of the horizontal portions, shade trunnion receiving portions slidably mounted on the horizontal portions for adjustment thereon and being 10 slotted for receiving the guide tongues therein, and set screws threaded in the horizontal portions for securing the trunnion receiving portions in adjusted positions.

5. JAMES SPERANZA. 15
